UNITED STATES PATENT OFFICE.

CHARLES HADENFELDT, OF SAN FRANCISCO, CALIFORNIA.

DESIGN FOR A BADGE.

SPECIFICATION forming part of Design No. 17,440, dated July 12, 1887.

Application filed June 1, 1887. Serial No. 240,009. Term of patent 3½ years.

To all whom it may concern:

Be it known that I, CHARLES HADENFELDT, a citizen of the United States, residing at the city and county of San Francisco, and State of California, have invented and produced a new and original Design for Badges, of which the following is a specification, reference being had to the accompanying drawing, forming part thereof.

10 My invention relates to a novel device for a pin or badge, which will be more fully explained by reference to the accompanying drawing, which is a front view of the badge.

15 The leading features of the design are a representation of the coat of arms of California in a central medallion or oval surmounted by the figure of a bear, while upon opposite sides are the representations of the American flag and the original bear flag, respectively. Beneath 20 this is a scroll, and beneath this again is a star.

25 A is a central medallion, which in the present case is made oval in shape, and has the figure of a woman with a bear at her feet, or what is known as the coat of arms of the State of California. Upon one side of this medallion

is represented a United States flag, B, depending from a staff, C, and curving around one side of the medallion. Upon the opposite side, curving in a like manner, is a banner or flag, D, depending from its staff C, bearing a 30 figure of a bear and a single star. Upon the top and above the medallion is the figure of a bear, and beneath the medallion, and extending around from the lower end of one flag to the lower end of the other, is a scroll or ornamental ground, F, and beneath this scroll is a star, G.

I claim -

35 The design for a pin or badge, the same consisting of the medallion surmounted by the 40 figure of a bear, having the scroll and star beneath, with the flags on either side, substantially as described and shown.

In witness whereof I have hereunto set my hand.

CHARLES HADENFELDT.
